ANODE FOR ELECTRON GUNS

John R. Beers, Bloomfield, N. J.

Application July 11, 1938, Serial No. 218,710

3 Claims. (Cl. 250—162)

This invention relates to an anode for electron guns. The anode comprises two sheet metal lens electrode elements arranged in a metal tube and spaced apart from one another, as shown on a greatly enlarged scale in the accompanying drawing. Each element comprises a disk having a peripheral flange fitting closely within the tube and by which it is frictionally held in a desired position within the tube, and the disks have small aligned perforations at their centers. Usually these perforations, which are about the size of a pin hole, are made by a punch which may leave sharp edges or projections at the margins of the perforations, which are objectionable from the electrical standpoint, and sometimes in forcing the elements into their desired positions in the tube the perforations are thrown out of exact alignment by warping of the disks.

20 The object of the present invention is to so
form the elements that the foregoing objections
will be overcome. In the preferred way of car-
rying out the invention the punched perforation
in the disk is made slightly larger than the re-
quired opening and a small eyelet is inserted in
25 the perforation in the disk, and by upsetting the
eyelet its ends are compressed against the sides
of the disk while the intermediate part is com-
pressed against the mandrel of the upsetting tool
which is of the exact diameter of the opening
30 which it is desired to produce in the lens. When
the mandrel is removed a true circular opening
of the desired diameter, with smooth surfaces,
is produced, and the disk is reinforced in its
35 central portion, which helps to prevent warping
of the element when it is pushed into its place
in the tube. Similar results may be accomplished
by drawing the metal of the disk in the process of
making the central perforation, producing a cir-
40 cular flange which is then upset and flattened
against one side of the disk by a suitable upset-
ting mechanism having a mandrel of the exact
diameter of the hole which it is desired to pro-
duce in the disk, so that when the mandrel is
45 withdrawn the hole in the disk will be a true
circular opening of the size desired, free from
sharp edges or projections, and the disk will be
reinforced at its central portion adjacent the
opening, which will aid in preventing distortion
50 of the disc when it is being pressed to its posi-
tion in the tube.

In the accompanying drawing in which the anode and its lens element are shown on a greatly enlarged scale,

55 Figure 1 is a central longitudinal section

through the anode, showing the lens elements with eyelets in the perforations.

Figure 2 is a central section through one of the discs with an eyelet fitting into the perforation in the disc.

Figure 3 is a similar view showing the eyelet ends flattened against the faces of the disk around a mandrel of an upsetting tool.

Figure 4 is a central section through one of the discs with the perforation in the disk made by drawing the metal, leaving a circular flange, and

Figure 5 shows the flange flattened against the disk around a mandrel, which, when removed leaves a true circular opening of the exact diameter desired and with a smooth edge. 15

Referring to the drawing, Figure 1, A indicates the anode comprising the metal tube *a* and the spaced lens electrode elements *b*. Each lens electrode element comprises a disk *1* having a peripheral flange *2* which fits closely within the tube and holds the disk frictionally in place. Small central perforations *3*, slightly larger than the openings desired are made in the disks by a punch, and eyelets *4*, inserted in the perforations, are shown with their ends pressed against the opposite sides of the disks. Figure 3 shows an eyelet fitted into the perforation in one of the disks, and Figure 4 shows the ends of the eyelet flattened around the margin of the opening in the disk, which is accomplished by applying pressure with a suitable upsetting tool having a mandrel *5*, the diameter of which is the same as that of the desired opening to be produced in the lens element, so that when the mandrel is withdrawn the opening through the eyelet will be of the exact diameter required and only smooth and rounded surfaces will be exposed to the electron stream passing through the opening. The lens element will also be strengthened in its central portion, by the eyelet, so that liability to distortion of the lens element will be lessened when force is applied to it in the subsequent handling of the lens element.

In Figures 4 and 5 are illustrated the method of accomplishing the desired result without the use of the eyelets. In this case, in forming the central perforation in the disk 1a of the lens element b', the metal is drawn, forming a circular flange 6 which is cut off to make it of suitable length. Then, as shown in Figure 5, a mandrel 7, of the exact diameter of the hole desired in the disc, is inserted in the opening 3a and the flange 6 is compressed against the face of the disk, as shown at 6a, leaving an opening of the 55

exact diameter of the mandrel, with smooth and rounded edges, when the mandrel is withdrawn. The lens element is also strengthened at its central portion by the overturned metal 6a which helps to prevent warping of the element in subsequent manipulation of the same.

What I claim is:

1. An anode for electron guns comprising a metal tube having spaced lens electrode elements therein, each element comprising a thin metal disk fitting closely within the tube and having a central perforation, and an eyelet affixed to the disk fitting within said perforation and covering the edges thereof, the end portions of the eyelet being upset against the opposite sides of the disc.
2. An anode for electron guns comprising a metal tube having spaced lens electrode elements therein, each element comprising a thin metal

disk fitting closely within the tube and having a central perforation with the metal of the disk drawn in making the perforation into the form of a circular flange, said flange being upset against the face of the disk, forming an opening through the disk of definite diameter and with smooth surfaces.

3. An anode for electron guns comprising a metal tube having spaced lens electrode elements therein, each element comprising a thin metal disk fitting closely within the tube, said disk having a small central perforation therethrough, and metal reinforcing means surrounding said perforation, said reinforcing metal being compressed against one face of the disk, whereby an opening of definite size and with smooth surfaces is produced.
